(57) **CLAIM**

The ornamental design for a rear combination lamp for motor scooters, as shown and described.

DESCRIPTION

FIG. 1: a front view of the rear combination lamp;
FIG. 2: a plan view of the rear combination lamp;
FIG. 3: a bottom view of the rear combination lamp;
FIG. 4: a right side view of the rear combination lamp;
FIG. 5: a left side view of the rear combination lamp;
FIG. 6: a perspective view of the rear combination lamp as seen from the right front side; and,
FIG. 7: a perspective view of the rear combination lamp as seen from the left front side.
The broken lines illustrate environmental structure only and form no part of the claimed design.
